UNITED STATES PATENT OFFICE.

J. GEORGE MARQUARDT, OF ERIE, PENNSYLVANIA, ASSIGNOR TO BLACK & GERMER, OF SAME PLACE.

JOURNAL-BEARING.

SPECIFICATION forming part of Letters Patent No. 331,311, dated December 1, 1885.

Application filed October 8, 1885. Serial No. 179,368. (No model.)

To all whom it may concern:

Be it known that J. GEORGE MARQUARDT, a citizen of the United States, residing at Erie, in the county of Erie and State of Pennsylvania, have invented certain new and useful Improvements in Journal-Bearings; and I do hereby declare the following to be a full, clear, and exact description of the invention, such as will enable others skilled in the art to 10 which it appertains to make and use the same, reference being had to the accompanying drawings, and to the letters of reference marked thereon, forming part of this specification.

15 My invention relates to journal-bearings; and it consists in the improvements herein-after set forth and explained.

My invention is illustrated in the accompanying drawings, in which Figure 1 is a perspective view of an emery grinding-machine constructed with my improved journal-bearings. Fig. 2 is a vertical cross-section of one of my improved journal-bearings on the line *x x* in Fig. 1. Fig. 3 shows an end view in 25 elevation of a modified form of my improved bearing.

Like letters refer to like parts in all the figures.

In the construction of my improved journal-bearing I construct the frame for supporting the bearing of any suitable or convenient shape desired—viz., in the form of an ordinary shaft-hanger, or in that shown in Fig. 1 of the drawings.

35 In the construction shown, A represents the stand of an ordinary emery grinding-machine adapted to stand upon the floor. On each end of the stand A are secured frames B, having ears C, which project upward at right angles 40 to the base of the frame B, to receive and support the ends of spiral springs D, which extend from the ears C to either side of the journal-boxes E, the springs D being secured in place by studs *e* on each side of the journal-box E, and set-screws *c*, which pass through

45 the ears C into buttons *c*, which enter the ends of the springs D. By means of these set-screws *c* the tension of the springs D may be increased or diminished, as desired.

50 In the bottom of the journal-boxes E, I secure stud-bolts F, which pass down through

the bottoms of the frames B, through holes *b* somewhat larger than the stud-bolts F, and are provided with nuts *f*. Upon these stud-bolts F, between the bottoms of the journal-boxes E and the upper surface of the frames B, I place spiral springs G, and on the stud-bolts F, under the bottoms of the frames B, I place spiral springs H, the tension of the springs G and H being adjusted by means of the nuts *f* on 55 the stud-bolt F, the journal-boxes being thus laterally supported by the spiral springs D and vertically by the spiral springs G H. The journal-boxes E thus supported are adapted to move or vibrate both laterally and 60 vertically with the shaft journaled therein.

In Fig. 3 I have shown a modified construction of my improved journal-bearing. In this construction the frames B (designated in this figure as B') are constructed with arms C' C', 70 projecting upward at an angle of about forty-five degrees from the base of the frame B', the ends whereof are provided with holes *b'*, somewhat larger than the bolts passing through them, as herein-after described.

On each end of the lower portions of the journal-boxes E' are ears *e' e'*. To these ears *e'* are hinged bolts F', which pass through the openings *b'* in the arms C'. Upon these bolts F', between the ears *e'* and the upper surfaces 8c of the arms C', I place spiral springs G', and under the arms C', on the bolts F', I place spiral springs H', which are secured by nuts *f'* on the ends of the bolts F', the tension of the springs G' and H' being adjusted by means of the nuts 85 *f'* as desired, the journal-boxes being thus supported by the spiral springs G' G' and H' H', so that they will yield to the vibrations of the shaft journaled therein, as required.

I have thus shown and described two forms 9c in which my improvement may be constructed, and in these constructions I have shown and described the springs as spiral springs. However, I can use any form of spring desired or springs constructed of rubber or other resili- 95 ent substance with equal facility.

I am aware that my invention may be utilized in the construction of many other forms of journal-bearings. Therefore I do not desire to limit myself to the particular forms of construction shown. I am also aware that others have heretofore suspended machine frames 100

and journal-boxes between rods from the ceiling to the machine-frame or the journal-box, and rods extending from the floor thereto, these rods being provided with springs of metal or 5 rubber, the patents of Huntington, No. 290,056, dated December 11, 1883, No. 297,133, dated April 2, 1884, and No. 307,115, dated October 28, 1884, being of this character; also, that journal bearings have been shown as suspended between vertical rods within a yoke, these rods being provided with springs of rubber or metal, the patent of Hardie, No. 317,345, dated May 5, 1885, being of this character. In these constructions, however, the suspending mechanism extends so much above the bearing that 15 their use is impracticable for use on emery grinders when it is necessary to handle the work over the machine. For example, in large stove-plate grinding, and in many other cases 20 when it is desirable to use small emery-wheels, these devices are impracticable, as the suspending mechanism extends above the wheel to such a distance that it is impossible to get 25 the work down to the wheel. I entirely avoid these difficulties by placing my spring mechanism below the level of the center of the emery-wheel, thus leaving the entire upper half of the periphery of the wheel, whatever 30 its size, free from obstruction, so that every portion of it can be used.

Having thus fully described my invention, what I claim as new, and desire to secure by Letters Patent of the United States, is—

1. In a journal-bearing, a supporting-frame 35 provided with springs, in combination with movable journal-boxes supported both vertically and laterally by such springs, so that

they will yield to vibrations of a shaft journaled therein, substantially as set forth.

2. The combination, with a journal-box frame 40 not extending above the top of the journal-box, of a movable journal-box, and springs communicating with the journal-box and with said frame, adapted to support and retain the journal-box in place, substantially as and for 45 the purpose set forth.

3. In a journal-bearing, the combination, with a supporting-frame, of a journal-box connected to said frame by means of springs on either side of and under said box, between said 50 box and the supporting-frame, and springs under said supporting-frame, connected to said box by bolts, substantially as and for the purpose set forth.

4. The combination, in a journal-bearing, of 55 the supporting-frame B, provided with arms C C, the side springs, D D, the springs G and H, and the stud-bolt F, with the journal-box E, substantially as and for the purpose set forth.

5. The combination, in a journal-bearing, of 60 the supporting-frame B, having arms C C thereon the adjusting-screws c c, side springs, D D, springs G and H, stud-bolts F, and the adjusting-nuts f, with the journal-box E, supported and held in place, substantially as and for the purpose set forth.

In testimony whereof I affix my signature in presence of two witnesses.

J. GEORGE MARQUARDT.

Witnesses:

JOHN S. RILLING,
H. M. STURGEON.
